TAPE DISPENSER

Theodore G. Schaible, Mountain View, N. J., assignor of one-half to Harold G. Kendall, Brooklyn, N. Y., and one-half to George H. Fritzinger, West Orange, N. J.

Application November 4, 1946, Serial No. 707,610

12 Claims. (Cl. 164—84.5)

1

This invention relates to a device for dispensing lengths of pressure-sensitive tape, and more particularly to an improved mechanical dispenser for such tape.

It is an object to provide a mechanical dispenser which is adapted particularly to meet the need in retail stores for an effective and simple means for dispensing different predetermined lengths of pressure-sensitive tape for sealing packages.

It is another object to provide a dispenser by which varying lengths of pressure-sensitive tape can be dispensed and picked up by hand in less time and with less conscious effort than is required by the dispensers of such tape now commonly used.

It is another object to provide an improved dispenser which is adapted for feeding out various selected lengths of pressure-sensitive tape across a table with the adhesive side facing upwardly whereby the lengths may be picked up by adhesive contact.

It is another object to provide a device which is adapted to enable strips of pressure-sensitive tape of predetermined length to be dispensed, picked up by the hand and severed from the supply roll by an ordinary simple manipulation of the hand.

Further objects and features of my invention are to provide a mechanical dispenser for pressure-sensitive tape which is arranged to enable the use of a light and inexpensive housing, which has a cheap and very simple operating mechanism and which is adapted to permit the new rolls to be easily installed and the machine to be maintained easily in working condition.

Other objects and features of my invention will more fully appear in the following description and the appended claims.

In the description of my invention, reference is had to the accompanying drawings of which:

Figure 1 is a vertical sectional view of a preferred embodiment of tape dispenser according to my invention, taken substantially on the line 1—1 of Figure 2;

Figure 2 is a top plan view of this dispenser;

Figure 3 is a fractional side elevational view showing the mechanism of the dispenser in its actuated position and the housing in section substantially on the line 3—3 of Figure 2; and

Figure 4 is a fractional sectional view taken substantially on the line 4—4 of Figure 1.

The present dispenser has a one-piece housing 10 which may suitably be cast of metal or moulded of plastic. This is a hollow housing open at the bottom and of rectangular shape as viewed from the top. The housing has a flat back wall 10a and sides 10b which are flanged outwardly at the bottom to give the housing a greater seating surface. At its forward portion, the housing has a

2

downwardly sloping top surface 10c which forms a table for supporting or backing the dispensed tape.

The top wall of the rearward portion of the 5 housing has a clearance opening 11 for a supply roll 12 of pressure-sensitive tape. This roll has a central core 13 at the axis of which there is removably mounted a shaft 14 the ends 14a and 14b of which extend beyond the sides of the core.

10 These shaft ends seat in bearings 15 and 16 which are depressions in the top wall of the housing at the sides of the clearance opening 11. Preferably, the bearings have different widths and the shaft ends have different diameters adapted to fit the respective bearings so that the roll can be mounted in only a correct position. In the present machine, this position is one wherein as tape is drawn forwardly from the roll, the adhesive side thereof will face upwardly away from the housing.

20 The table 10c is suitably curved on an arc about a center line 17 at the base of the housing. Between this table and the supply roll at a slight distance above the housing there is a roller 18 25 journaled on a horizontal transverse shaft 19 that is carried by an upright standard 20 at the left side of the housing. This roller engages continuously the adhesive side of the tape T drawn from the supply roll and tends to hold the tape in advance thereof in a forward direction and adjacent to the table 10c.

30 The feed mechanism for mechanically drawing the tape from the supply roll comprises a feed member 21 which has a surface 21a for holding to the tape by contact with the adhesive side thereof. Preferably, I mechanically hold the tape in adhesive contact with this surface during the feed stroke. This is done by providing a member

rear of this slot there is a transverse opening 28. This is a clearance opening through which the members 21 and 22 are passed in assembling the feed mechanism in the housing.

The feed member 21 is a turned-over portion of a lever 34 that is pivoted at 35 to the lever 23 at the left side of the latter. The lever 34 extends upwardly also through the slot 27, and is biased over center by a tension spring 36 which is at the right side of the lever 23, the spring being connected between a lug 37 on the lever 23 and a right bent lug 38 on the lever 34. Being at the right side of the lever 23, the spring 36 holds the lever 34 slidably against the left side of the lever 23 and, as a result, the pivot 35 is permitted to be a simple pivot stud, as shown. When the feed member 21 is in its lowermost position, it is urged by the spring 36 against the backing member 22 as shown in Figure 1, but as the lever 34 is swung upwardly the spring 36 passes over the pivot 35 and then urges the feed member into its released position shown in Figure 3, the angular movement of the lever 34 being typically about 30 degrees. The released position of the feed member is defined by the abutment of a lug 39 on the lever 34 against a lug 40 on the lever 23. To prevent a metal clang when these lugs meet, the lug 40 is covered with rubber 41.

At the front of the housing the lever 23 has a forwardly projecting arm 23b which extends through a slot 29 in the table 10c. On the end portion of this arm there is secured, by pins 30, a handle 31 which extends throughout the width of the housing and overlies the front portion of the table 10c. As the handle 31 is depressed the members 21 and 22 are carried forwardly across the table 10c, and when the handle is released these members are returned by a tension spring 32 connected between the lever 23 and a pin 33 on the housing. The returned position of the lever 23 is defined by its abutment against the housing at the rear edge of the opening 28. In its movement the lever 23 is held stable against sidewise play by its engagement with the slots 27 and 29.

On the lower portion of the lever 34 there is a lug 42 bent leftwardly towards the left wall of the housing. As the handle 31 is depressed through the final portion of its downward movement, the lug 42 impinges against a stationary pin 43 on the housing and swings the lever 34 upwardly to move the feed member 21 into its released position. When the handle is released it is returned by the spring 32 as are also the members 21 and 22 with the feed member 21 being retained in its raised or released position by the spring 36. As the lever 23 nears the end of its return travel, the lug 42 is impinged against a second pin 44 on the housing to swing the lever 34 downwardly and bring the feed member into engagement with the tape T backed by the member 22.

The feed member thus engages the adhesive side of the tape and takes hold of the tape by the adhesion of the tape to its surface 21a. As the handle 31 is depressed to swing the feed member forwardly the pull of the tape on the feed member causes the latter to be drawn against the backing member 22 because the pivot 35 is in front of and below the backing member. The tape is accordingly pressed into adhesive contact with the feed member with a pressure that is proportional to the feed resistance of the tape and, as a result, the "grip" of the feed member on the tape varies according to the feed resistance. This is a highly advantageous feature because it results in the

tape being held positively by the feed member without slippage even though the dispenser is actuated sharply as by an impact blow against the handle 31.

As the handle 31 is depressed a length of tape of preferably about $1\frac{1}{4}$ " is drawn from the supply roll and then the feed member 21 is disengaged from the backing member 22 as above described. The disengagement of the feed member is effected by advancing it in an oblique direction away from the backing member so that its surface 21a is turned to angles greater than 180° from the tape leading therefrom to the supply roll. As a result the tape supply is stripped free from the feed member in response to the said resistance of the tape caused in part by the adherence of the tape to the roller 18 and in part by the adherence of the outer convolution to the back side of the next adjacent convolution of the supply roll. The dispensed length of tape which is so freed from the feed member is held adjacent to the backing member 22 under the guiding influence of the roller 18 as shown in Figure 3. Upon the release of the handle 31, the backing member is returned along the non-adhesive side of the delivered length of tape and the feed member is moved in a return path at a clearance distance above the tape until it nears the end of its return travel, whereupon it is reengaged with the tape as above described. If a length greater than $1\frac{1}{4}$ " is wanted the handle 31 is actuated several times in succession, depending upon the particular length desired.

Secured by screws 45 to the feed member 21 is a blade 46 which has a cutting edge 46a spaced ahead and preferably slightly above the feed member. It is against this cutting edge that the delivered length of tape is to be drawn by hand and severed from the supply roll. The distance of the cutting edge ahead of the feed member is at least as great as the distance of movement of the backing member 22 following the disengagement of the feed member therefrom—which is the distance between the dash-dot and full-line positions of the backing member shown in Figure 3. By so positioning the cutting edge relative to the feed member the delivered tape will always extend beyond the backing member and will not be buckled back on itself as the backing member is returned. After the members 21 and 22 are returned, the delivered length of tape in advance thereof is picked up by "touch"—i. e., adhesive contact of the finger of the hand with the upper adhesive side of the tape—and is then gripped by placing the thumb therebelow as the tape is raised from the table 10c. As an incident to lifting the tape from the table, it is drawn against the cutting edge 46a and is cut off from the supply roll. Thus, upon performing a simple manipulation as the hand is removed from the handle 31, a desired length of tape is picked up in such position that it can conveniently be applied to seal a package or affix it for any other purpose. Since the tape is delivered by merely striking a handle one or more times, depending on the length desired, without having to take hold of the tape and draw it by hand from the roll, and can then be picked up by a simple manipulation as the hand is removed from the handle, it will be understood that the present machine is adapted to enable lengths of pressure-sensitive tape to be dispensed in less time and with less conscious effort than can be done with the dispensers commonly used. Moreover, because the tape is delivered by pressing

downwardly on the handle, the housing can be made relatively light and at reduced cost.

I have hereinabove described the member 21 as a feed member and the member 22 as a backing member, which is in accord with their prime functions. From another viewpoint, however, these members may be referred to as clamping members because in their operation they do clamp the tape and hold thereto by the adhesive contact of the tape with the member 21.

I have herein particularly described a preferred embodiment of my invention but it will be understood that this embodiment is illustrative and not limitative of my invention as the same is subject to changes and modifications without departure from the scope of my invention, which I endeavor to express according to the following claims.

I claim:

1. In a machine for dispensing lengths of pressure-sensitive tape, including a frame and a supply roll of tape rotatably mounted on said frame: the combination of a pair of cooperating tape-clamping members mounted for reciprocative movement with respect to said frame, means pivoting the one clamping member at the adhesive side of the tape to its cooperating clamping member on a pivot axis ahead of said clamping members with respect to their direction of advance, actuating means for advancing said clamping members to pull a length of tape from said roll and for returning the clamping members for a succeeding length, and means associated with said one clamping member for pivoting it about said axis to release it from the tape during the final part of each advance stroke of said actuating means and for reengaging it with the tape when the clamping members are returned.

2. In a machine for dispensing lengths of pressure-sensitive tape from a supply roll, said machine including a frame and means rotatably mounting said roll on said frame: the combination of a pair of tape-clamping members reciprocable from and to an initial position with respect to said frame, means pivotally connecting the one clamping member at the adhesive side of the tape to its cooperating clamping member on a pivot axis which is offset from the non-adhesive side of the tape and positioned ahead of the clamping members with respect to their direction of advance whereby said one clamping member is movable in an advancing direction obliquely away from the other clamping member, means progressively actuatable for advancing said clamping members to pull a length of tape from said roll and thereupon further advancing said one clamping member in an oblique direction away from the other clamping member about said pivot axis to release it from adhesive contact with the tape, and means associated with said one clamping member and effective when said actuatable means reaches the end of its forward travel for holding said one clamping member displaced from said other clamping member until the clamping members are returned to initial position.

3. In a machine for dispensing lengths of pressure-sensitive tape from a supply roll: the combination of a tape feed member having a surface for contacting the adhesive side of the tape, said feed member being mounted for reciprocative movement; means for advancing said feed member to draw a length of tape from said roll and thereupon release the feed member from adhesive contact with the tape; means for reengaging said feed member with the tape when the same is returned; and a cutting edge carried with said feed

member and adapted for severing said length from the tape supply upon drawing said length thereagainst while the feed member is in its returned position.

4. The method of pulling a length of tape against a resisting force which comprises holding the tape in adhesive contact with a surface, advancing said surface to exert a pull on the tape while concurrently pressing against the non-adhesive side of the tape to prevent slippage of the tape relative to said surface whereby to cause the tape to be pulled against said force, withdrawing said pressure from the non-adhesive side of the tape and turning said surface to more than 180° from the adhesive side of the tape extending therefrom, and further advancing said surface while the pressure on the non-adhesive side of the tape is withdrawn and said surface is at more than 180° from the tape extending therefrom whereby to cause the tape to be stripped from the surface by said resisting force.

5. A reciprocatory feed mechanism for dispensing lengths of pressure-sensitive tape from a supply roll comprising a reciprocable feed member having a surface for releasably contacting the adhesive side of the tape, means for reciprocating said feed member, and a cutting edge carried with said feed member for severing the dispensed lengths from the tape supply as said lengths are picked up and drawn against said edge.

6. In a machine for dispensing lengths of pressure-sensitive tape from a supply roll: the combination of a substantially horizontal surface for supporting the dispensed length of tape; means engaging the adhesive side of the tape drawn from said roll for holding the dispensed lengths of tape adjacent to said surface, a feed member having an initial position adjacent to said holding means wherein it engages the adhesive side of the tape, means for advancing said feed member across said surface while the feed member holds to the tape to pull the same from the roll and for thereupon further advancing the feed member to release it from the tape, means for returning said feed member in a path substantially above said surface and thereupon reengaging it with the adhesive side of the tape, and a cutting edge carried with said feed member for severing the dispensed length of tape from the tape supply as said length is picked up from said surface and drawn against said edge.

7. In a machine for dispensing lengths of pressure-sensitive tape from a supply roll: the combination of a table over a rearward portion of which said tape lengths are delivered with the adhesive side facing upwardly, said table having a downwardly sloping forward portion, a pair of horizontal vertically-spaced tape-clamping members overlying the rearward portion of said table and movable forwardly and rearwardly thereacross, a handle at the front of said table depressible to advance said clamping members and pull a length of tape from said roll, means for raising the upper one of said clamping members in the final portion of the downward movement of said handle to release it from the tape and for holding the same raised until the clamping members are returned, and means mounted on said upper clamping member having a cutting edge for severing said lengths from the tape supply as the same are drawn thereagainst while the clamping members are in their returned positions.

8. In a machine for dispensing lengths of pressure-sensitive tape from a supply roll: the combination of a table having a flat rearward portion

and a downwardly sloping forward portion, means for pulling lengths of tape forwardly across the rearward portion of said table with the adhesive side of the tape facing upwardly, a blade carried with said tape-pulling means and against which the delivered lengths are drawn and severed from the roll as an incident of picking said lengths up from said table, and a handle depressible to actuate said pulling means, said handle being positioned directly ahead of said delivered tape lengths.

9. In a machine for dispensing lengths of pressure-sensitive tape from a supply roll, including a frame: the combination of a reciprocable member movably mounted on said frame and adapted for backing the non-adhesive side of the tape drawn from said roll, means engaging the tape drawn from said roll and tending to hold the tape in advance thereof adjacent to the path of movement of said backing member, a clamping member at the adhesive side of the tape and cooperating with said backing member, means for simultaneously advancing both of said members while the same are engaged to pull a length of tape from said roll and thereupon advancing said clamping member in an oblique direction away from said backing member to release the former from adhesive contact with the tape, means for holding said clamping member displaced from said backing member as said members are returned, and means causing the clamping member to reengage the tape upon the return of said members.

10. The combination set forth in claim 9 wherein said clamping member is pivotally connected to said backing member for advance movement in an oblique direction away from said backing member, including over-center means cooperating with said clamping member for releasably holding the same in its released and engaged positions respectively.

11. In a machine for dispensing lengths of pressure-sensitive tape from a supply roll: the combination of a hollow unitary housing having a forward table portion and having a rearward portion adapted for pivotally supporting said roll, a transverse shaft mounted on a lower portion of said housing, a reciprocable lever pivoted on said shaft, a transverse member on said lever and overlying the rearward part of said table for backing the non-adhesive side of the tape drawn from said roll, means on said housing between

10

said backing member and said roll for holding the tape strips in advance thereof normally in a direction substantially parallel to said table and adjacent to said backing member, a clamping member cooperating with said backing member and pivoted to said lever at a point to the front of and below said backing member, over-center means for releasably holding said clamping member in engaged and released positions respectively, and abutments on said housing against which said clamping member is impinged to operate the latter into said released and engaged positions during the final portions of the advance and return strokes of said lever.

12. A reciprocatory mechanism for pulling lengths of pressure-sensitive tape from a supply roll comprising a frame, reciprocable tape-clamping means comprising a backing member at the non-adhesive side of the tape movably mounted on said frame and a cooperating feed member for adhesively contacting the adhesive side of the tape backed by said backing member, actutable means for advancing and returning said tape-clamping means with respect to said frame, means pivotally connecting said feed member to said backing member on an axis offset from the non-adhesive side of the tape engaged by said clamping members and positioned ahead of said backing member with respect to the direction of advance of said clamping means whereby with increasing feed resistance of the tape said feed member is pressed against said backing member with increasing force, and means engaging said feed member in the final portions of the advance and return strokes of said clamping means for moving said feed member away from and back to said backing member respectively.

THEODORE G. SCHAILBE.
